UNITED STATES PATENT OFFICE.

OSCAR L. SMITH, OF GRAND RAPIDS, MICHIGAN, ASSIGNOR TO SAMUEL D. YOUNG,
TRUSTEE, OF GRAND RAPIDS, MICHIGAN.

DISPLAY DEVICE.

1,099,132.

Specification of Letters Patent.

Patented June 2, 1914.

Application filed January 20, 1912. Serial No. 672,412.

To all whom it may concern:

Be it known that I, OSCAR L. SMITH, a citizen of the United States, residing at Grand Rapids, in the county of Kent and State of Michigan, have invented an Improvement in Display Devices, of which the following description, in connection with the accompanying drawings, is a specification, like letters on the drawings representing like parts.

The invention to be hereinafter described relates to display devices for exhibiting goods, and more particularly to such display devices wherein a rotatable rack is employed for supporting the goods to be displayed and is movable to and from a position within a case or cabinet.

Economy of floor space in stores and like places demands that such display devices be made to occupy a minimum amount of area. It is also desirable to protect the goods or merchandise displayed by the use of an inclosing case or cabinet, and in order that the goods thus protected may be readily inspected or shown a prospective purchaser, it has been proposed heretofore to support the goods or merchandise upon a rack movable to and from a position within the case, and to mount the rack or rotative movement when at the front of the case. Under these conditions it has heretofore been proposed in a prior Patent No. 987,183, granted to me March 21, 1911, to prevent injury to the case or cabinet by restraining the rack from free rotative movement as it was moved into and out of the case, but the rack was intended to be rotated by hand when in outer position to bring the rack into such proper relation with the case, that is with the rack bars parallel to the back wall thereof, that it could be moved thereinto without injury to the case.

One of the aims and purposes of the present invention is to provide means, in the general character of display device noted, whereby the rack may be automatically turned into its proper predetermined relation with the case without special attention on the part of the attendant who is usually unskilled in mechanical matters and their operative characteristics, so that when moved into the case the rack will not contact with or injure it. This and other features of the

present invention will more fully appear from the following description and accompanying drawing of one form of means for carrying the invention into practical effect, it being understood that it is not confined to the particulars shown and described, but is definitely set forth in its true scope by the claims.

In the drawing:—Figure 1 is a side elevation of a display device showing the case and the rotatable rack movable to and from a position within the case; Fig. 2 is a detached detail of a locking device to be described; Fig. 3 is an enlarged sectional plan view of a part of the case and a carriage for supporting the rotatable rack, showing one form of the present invention, some of the parts being broken away; Fig. 4 is a section on the line 4—4, Fig. 3; and Fig. 5 is a section on the line 5—5, Fig. 4.

The show case or cabinet 1 may be of any usual or desired form and character, but is illustrated as comprising a base and glass panels 2 suitably supported in frames 3 joined together to constitute sides, back, and top, as usual in such devices.

The rack, Fig. 1, may be of any usual design suited to the conditions of use, and, as one form thereof, is shown as comprising the bars 4 from which garments or the like may be hung. The bars 4, constituting the rack, may be appropriately supported on the arms 5, 5 mounted at the upper portion of a support 6, Figs. 3, 4 and 5, which is itself sustained in suitable manner for bodily movement to and from a position within the case. In the illustrated form of the invention, the support 6 is shown as a rotatable upright shaft and the arms 5, 5 are secured thereto, and the said shaft is shown as rotatably supported by a carriage movable to and from a position within the case. This general arrangement is found to be a good, practical and convenient form, but it is to be understood that so far as the essentials of the invention are concerned the parts may be otherwise related, and the carriage, as well as the rack, be changed, the requirement in this respect being that the rotatable rack may be so mounted that it may be moved to and from a position within the case or cabinet.

Secured to the base of the case and extend-

ing from front to rear thereof are suitable tracks 7, Figs. 3, 4 and 5, upon which ride the rollers 8 secured to their respective shafts or axles 9 mounted in bearings 10 and 11 at the rear and front respectively of the carriage 12, Figs. 3 and 4. The carriage is preferably of a three arm shape as indicated in Fig. 3, and the shafts or axles 9 preferably rotate with the rollers 8 as they move over the tracks 7, said shafts or axles 9 thus constituting stable and efficient means for sustaining the weight of the parts and the rack load. The tracks 7 may be appropriately supported upon the base of the case, as by means of the tie beams 13 to which they may be secured, and said tracks, as well as the main body of the carriage 12, are preferably disposed beneath the floor 14 of the case, Figs. 4 and 5.

Rising from the main body of the carriage 12 is the flange 15 which extends through the slot 16, Figs. 4 and 5, formed in the floor of the case, and has formed therewith the socket portion 17 from which rises the sleeve bearing 18 for the shaft or support 6. The sleeve bearing may be connected to the portion 17 in any suitable manner, but is here shown as screw-threaded thereto.

Seated upon the bottom of the socket portion 17 is a ring 19, Fig. 4, upon which travel the anti-friction balls or rollers 20 supporting a flange or collar 21 secured to the shaft 6, the construction being such that the parts described constitute a thrust bearing for the shaft 6 and its load and offer little resistance to rotative movement of said shaft and perforce the rack connected thereto, while suitable lateral support for the shaft 6 is afforded by the sleeve bearing 18 and the lower portion 22 of the shaft 6 where it passes through the socket portion 17 of the carriage. The parts so far described may vary in form and character as well as in their relation within the true scope of the invention, but as shown and described they constitute a convenient and practical form of rotatable rack and its mounting permitting the rack to be moved to and from a position within the case.

As hereinbefore noted, the present invention contemplates means for automatically turning the rack into a predetermined relation with the case, so that when bodily moved with relation to the case, the rack will not injure it. In Fig. 1, the rack shown in full lines as at the front position and turned partially around so that if moved into the case at such time or whenever the rack is not parallel to the back wall of the case the rack would strike and injure or break the same. The dotted line position, however, shows the rack at its position within the case, the rack or bars 4 being parallel to the back of the case. Obviously with the rack in such

parallel relation with the back of the case, it may be moved from front to rear position, or bodily with relation to the case without danger of injuring the case.

One means for effecting the automatic action of the rack is shown by the drawings as comprising a member rotatable with the rack and a non-rotatable member secured to the carriage. In the form shown, the rotatable member comprises plates 23 and 24 secured to the lower portion of the rack support or shaft 6 so as to rotate therewith. As one means to this end, the end portion 25 of the shaft or support 6 may be made non-circular in cross section to engage correspondingly shaped openings in the plates 23, 24. The two plates 23 and 24 are separated by rolls 26, 26, Fig. 4, mounted on pins 27 passing between and secured to said plates at substantially diametrically opposite points. The plates and their separating and diametrically disposed rolls 26, 26 are suitably secured in place, as by a nut 28 threaded to the lower end of the shaft 6, or by other means if desired, and constitute, in effect, a

Pivotedly mounted at 29, 29 to the carriage are the members or arms 30, Figs. 3 and 4, the free ends 31 of which are adapted to engage the diametrically disposed rolls 26. The members or arms 30 are normally under the influence of a spring which tends constantly to move the arms toward each other into the position indicated by Fig. 3. As one convenient form of such spring control, there is a bolt 32 passed through the arms 30 and having head portions 33 one at each end. Between each of the head portions 33 and the adjacent arm 30 is a spring 34, one end of which is seated against the head 33 and the other against a suitable bearing 35 carried by the arm 30, the construction being such that while the arms or members 30 are thus normally held yieldingly pressed toward each other and against the rolls 26 when the parts are in the position indicated in Fig. 3, the said yielding spring controlling means permits the free end portions 31 of the arms 30 to separate when the rack and perforce its connected rotatable member carrying the rolls 26 is rotated. When the rolls 26 are thus carried from the position indicated in Fig. 3 to separate the ends 31 of the arms 30 and are released from the hands of the operator, the arms 30 at once assert their automatic control of the rack to rotate the rack into a predetermined relation with respect to the case, so that the rack may then be moved, with relation to the case without danger of injury thereto.

While the members or arms 30 are herein shown as one convenient form of this feature of the invention, it is to be understood that the invention is not restricted thereto but

is generic in character with respect to the automatic control of the rack to return it to a predetermined relation with the case when such predetermined relation has been disturbed.

The rotatable member connected to the rack to rotate therewith constitutes, in effect, a cam, which, when the rack is partially turned acts upon the non-rotatable member to move it against spring tension, with the result that when the rack has been turned more or less from its parallel relation with the case and released, the spring tensioned non-rotatable member, whether formed of one or more arms, acts upon the rotatable member to automatically bring the rack into the desired predetermined parallel relation with the back wall of the case, in which position it may be moved bodily relative to the case without danger of breaking the glass or injuring the case.

It may sometimes be desirable to provide against possibility of the rack being rotated by any extra force applied thereto as it is being moved into the case, and while some means to this end may be conveniently employed in connection with the self righting feature, it is not essential thereto and may or may not be employed. As one practical means to this end, the pins 27 on which the rolls 26 are mounted are preferably extended some distance below the lower plate or disk 24 and constitute one part of a device to thus restrain rotative movement of the rack while it is being moved to and from its position within the case. Co-acting with the ends 36 of the pins 27 is a part 37, which, if desired, may be formed circular, as indicated in Fig. 2, and is provided with openings 38 diametrically disposed to engage the projecting ends of the pins 26, when the rack has been automatically rotated to such position with relation to or parallel with the case that it may be moved into the case without danger of injury to the same.

The part 37 is carried by an arm 39, Figs. 2 and 4, which is pivoted to the carriage at 40 and carries near its free end a roll 41 which is adapted to ride on the upper edge portion of a central trackway 42, Figs. 4 and 5. The trackway 42 has an inclined end portion 43.

From the construction described, it will be apparent that when the rack is rotated by the automatic action of the rotating device into predetermined position such that it will not contact with the case when it is moved bodily with respect thereto or into the case, the ends of the pins 37 are opposite the openings 38 in the part 37, so that if the rack at this time be moved inward or toward its inner position with respect to the case, the roller 41 will ride up the inclined portion 43 of the trackway 42 and

cause the openings 38 to engage the ends 36 of the pins 27, with the result that the rack is then restrained from rotative movement while it is bodily moved to and from a position within the case. If, however, the automatic device has not rotated the rack in such position that it will not injure the case as it is moved toward its position within the case, and the rack be then forced inward, the part 37 by its non-perforated portion will contact with the ends of the pins 27 and prevent movement of the rack to its position within the case, and thus avoid injury thereto. As soon, however, as the rack is rotated to such position that it will not injure the case as it is moved toward its inner position, the ends of the pins 27 will register with the openings 38 in the part 37, thus permitting the part 37 to rise as the roller 41 moves over the incline 43 and permit the rack to be moved to its inner position within the case.

Obviously, changes and variations may be made in the details and particular means described for carrying the invention into practical effect with respect to the automatic rotation of the rack as hereinbefore described, and also with respect to the particulars of the means for preventing rotation of the rack as it is moved bodily toward and from its position within the case.

While in the illustrative form of the invention the cam member is shown as formed by the plates 23 and 24 and pins or rollers 26, and while the non-rotatable member of the self righting device is shown as formed of two spring actuated arms, it is to be understood that the cam member may be otherwise formed and that the non-rotatable member may be constituted by a spring actuated arm or other device, the essentials in these respects being that such non-rotatable member may act upon the cam member to turn it and the connected rack, when the latter is turned from parallel relation with the back wall of the case or cabinet and released.

If desired, a spring 44 may be employed to assist in depressing the end of the part 37 when the rack is moved to its outer position.

In operation, the doors of the case, if used, may be opened and the rack moved to front position where it may be rotated around and around in either direction through 360° to show the garments. When the salesman or saleswoman has finished showing the goods and releases the rack prior to pushing it into the case, the rack, if not parallel with the back wall of the case, will automatically right itself, that is, it will be automatically turned to bring it parallel with the back of the case, in which position it may be pushed back without danger of breaking the glass or injuring the case.

What is claimed is:

1. In a display device, the combination of

a case, a rotatable rack movable to and from a position within the case, means including a spring-operated device acting automatically to rotate the rack to a predetermined position with reference to the case when the rack is at its outer position, and a device co-acting with a part of said automatic means to restrain rotative movement of the rack after it has been automatically moved into said predetermined position as it is bodily moved to and from its position within the case.

2. In a display device, the combination of a case, a rotatable rack movable to and from a position within the case, and automatic means for turning the rack into parallel relation with the case when said rack is turned from such parallel relation and released, said means comprising a cam member connected to the rack and a spring actuated arm bearing against said cam member.

3. In a display device, the combination of a case, a carriage movable to and from a position within the case, a rack movable with said carriage and mounted for rotative movement, and spring actuated means to rotate the rack into a predetermined relation with the case that it may not injure the case when bodily moved with respect thereto, said means comprising a rotatable member and a non-rotatable member, one connected to the rack and the other to the carriage.

4. In a display device, the combination of a case, a carriage movable to and from a position within the case, a rack movable with said carriage and mounted for rotative movement, and automatic means acting normally to rotate the rack into a predetermined relation with the case that it may not injure the case when bodily moved with respect thereto, said means comprising a member rotatable with the rack and a member on the carriage yieldingly acting upon the rack member.

5. In a display device, the combination of a case, a rotatable rack movable to and from a position within the case, and automatic spring actuated means acting normally to rotate the rack into a predetermined relation with the case that it may not injure the case when bodily moved with respect thereto.

6. In a display device, the combination of a case, a carriage movable to and from a position within the case, a rack movable with said carriage and mounted for rotative movement, automatic means acting normally to rotate the rack into a predetermined relation with the case that it may not injure the case when bodily moved with respect thereto, said means comprising a member rotatable with the rack, arms pivotally mounted on the carriage and disposed at opposite sides of the rotatable member, and means to yieldingly force the arms against the rotatable member.

7. In a display device, the combination

of a case, a carriage movable to and from a position within the case, a rack rotatably supported by the carriage, automatic means acting normally to rotate the rack into a predetermined relation with the case and comprising a rotatable member connected to the rack and having bearing portions on opposite sides of its axis of rotation, and co-acting arms mounted on the carriage and yieldingly engaging the said bearing portions.

8. The combination with a cabinet and a revoluble rack movable into and out of the cabinet, of means for automatically righting the rack into a predetermined position relatively to the cabinet when rotated a partial revolution in its position and released, said means comprising a cam rotatable with the rack and a non-rotatable member, and means for forcing said non-rotatable member against the cam.

9. The combination with a cabinet and a revoluble rack movable into and out of the cabinet, of means including a spring actuated device permitting the rotation of the rack in its outer position and also acting, when the rack is turned from parallel relation with the case and released, to automatically adjust it into its normal position relatively to the cabinet.

10. The combination with a goods display rack, a reciprocating carriage and a revoluble standard mounted thereon and supporting the rack, of two spring arms forming a guide and located in alinement with the line of travel of the carriage, and an arm on the standard fitted between said spring arms and acting when the rack is at outer position and partially rotated to separate said spring arms.

11. In a display device, the combination of a case, a rotatable rack mounted for movement to and from a position within the case, a cam connected to the rack, a device engaging said cam, and means for yieldingly forcing said device against the cam to cause the latter and the connected rack to turn to a predetermined position with respect to the case when the rack is turned from said predetermined position and released.

12. In a display device, the combination of a case, a rotatable rack mounted for movement to and from a position within the case, a cam connected to the rack, a device engaging said cam, means for yieldingly forcing said device against the cam to cause the latter and the connected rack to assume a predetermined position with respect to the case when the rack is turned from said predetermined position and released, and acting as the rack moves to and from the position within the case to restrain rotation of the rack.

13. In a display device, the combination

of a case, a rotatable rack movable to and from a position within the case, and means including a spring device tensioned by partial rotation of the rack and acting when the rack is released to automatically turn the rack into a predetermined position with relation to the case.

In testimony whereof, I have signed my name to this specification, in the presence of two subscribing witnesses,

OSCAR L. SMITH.
